[57] CLAIM

The ornamental design for a printer, as shown and described.

DESCRIPTION

FIG. 1 is a front top and right side perspective view of a printer showing my new design;

FIG. 2 is another perspective view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a left side elevational view thereof;

FIG. 8 is a right side elevational view thereof; and

FIG. 9 is a sectional view taken on line IX—IX of FIG. 3 with the interior construction omitted;

The broken lines representation of paper and letters in FIG. 2 is for illustrative purposes only and forms no part of the claimed design.
